UNITED STATES PATENT OFFICE

2,089,107

HAIR WAVER

Bernhard M. Beskow, Miami Beach, Fla.

Application August 28, 1936, Serial No. 98,376

10 Claims. (Cl. 132—41)

This invention relates to devices or appliances for the waving of hair and more particularly to devices of this character which are adapted to impart waves or undulations to the hair in both the vertical and horizontal planes.

The subject matter of the present specification is somewhat similar to those of my Patents Nos. 2,002,487 and 2,014,164 and reference may be made to those patents for certain of the broader objects and principles of construction and operation of devices of this general type. Briefly, it may be stated that the purpose of the present invention is to provide a hair waver by means of which it is possible for the user to apply and set a wave in her hair without expert assistance; the waver being light in weight, simple in construction and operation, readily insertable in and removable from the hair, and capable of being manufactured at low cost.

More specifically, it is an object of the invention to provide a hair waving appliance having cooperating elements for applying a wave to the hair which comprises a series of undulations disposed in vertical planes with reference to the scalp, the waver also having other portions for modifying such waves to give them a curvature or undulation in a lateral direction or parallel with the scalp; the latter wave-modifying portion being readily detachable from the main portion of the waver.

In its preferred embodiment, the invention contemplates the provision of a waver which consists essentially of a pair of members between which the hair is initially seized, one of these members being subsequently expandable, the latter member for this purpose, being provided with a portion which is transversely shiftable to more closely confine the hair and to impress the desired vertical wave therein. A third member comprises a detachable portion of one of the first named members and is also shiftable with respect to the main portion thereof to apply a horizontal curvature to the hair being treated.

Other objects and features of novelty will be apparent from the following specification when it is read in connection with the accompanying drawing in which one embodiment of my invention is illustrated by way of example.

In the drawing:

Figure 1 is a top plan view of a hair waver embodying the principles of my invention; a portion of one of the elements thereof being broken away to show the construction of the device more clearly;

Figure 2 is a longitudinal central sectional

view through the device illustrated in Figure 1; certain operative positions being shown in broken lines;

Figure 3 is a view in perspective of the detachable horizontal wave forming portion of the appliance;

Figure 4 is a transverse sectional view of the waver taken on line 4—4 of Figure 2;

Figures 5 and 6 are similar views taken on line 5—5 of Figure 2 showing the device with the 10 expandible member in released and operative positions respectively; and

Figures 7 and 8 are fragmentary views in substantially horizontal section taken on line 7—7 of Figure 6 and indicating the released and operative positions respectively of the supplemental horizontal wave forming element.

In the embodiment of the invention illustrated in the drawing there are provided two basic elements of the device which are designated A and B, these members being pivotally connected as at c. The member A comprises a curved metallic element 10 which is preferably tapered at one end as indicated at 11. Turned up side flanges 12 are also provided throughout the length of the member 10. At the opposite end of the element 10 there are formed a pair of laterally spaced upstanding lugs 14 provided with eyes which form hinge portions for the reception of the inwardly turned ends 15 of the wire 16 constituting the essential element of the member B, which it will be readily seen assumes the roughly rectangular shape clearly illustrated in Figure 1 of the drawing. The side portions of the wire frame 16 may be outwardly bowed as at 17 if desired.

Between the hinge lugs 14 and surrounding the inwardly directed ends 15 of the wire 16 there is provided a sleeve element 18. This sleeve element not only provides means for covering and concealing the ends 15 of the member 16 but provides a keeper for a shiftable portion of the device which will now be described.

The member A further comprises a flexible element 20 which may be secured adjacent the end 11 of the element 10 as by means of the punched rivet-like connection 21 and is bent rearwardly to provide the curved nose portion 22 behind which the forward portion 23 of the wire 16 forming the member B may snap when the device is in closed position. The widened mid-portion of the strip 20 is slotted as at 25 for a purpose which will be later explained, and the rearmost portion of the strip 20 is again narrowed as shown at 27 so that it may pass between the lugs 14 of the base member 10 and beneath

the sleeve 18. The portion 27 of the flexible member 20 is downwardly curved as clearly shown in Figure 2 of the drawing and is provided at its end with an upright handle or manipulative portion 28 beyond the fairly sharply bent bight portion 29.

Slidably mounted upon the side rails of the wire 16 and comprising a detachable part of the member B, is the supplemental element 30 by means of which a horizontal or lateral component may be applied to the vertical wave or undulation of the hair. The element 30 comprises a strip of metal or similar material of somewhat arched configuration following substantially that of the base member 10 and provided at its four corners with downwardly projecting legs 32. Each of these legs is provided with a clip 33 which has a substantially circular opening 34 therein for the reception of the wire portion 16 of the element B when the element 30 is applied. The clip is also provided with a restricted opening 35 which is adapted to cause it to snap over the wire 16 when the element is applied or detached. The member 30 is not as long as the frame 16 forming the member B and the legs of the member 30 are adapted to slide along the wire 16 for a limited distance during the application of the device to the hair. Centrally of the body portion of the member 30 there is provided a series of teeth 36 which are adapted to register with the elongated opening 25 in the strip 20 which forms a part of the member A. These teeth may be conveniently formed by punching portions of the metal of the member 30 downwardly as indicated.

The application and operation of the device to the hair will now be described. The members A and B are initially parted as shown in the dot and dash lines of Figure 2 by swinging these members apart about the pivot c, and the sharply pointed member A is pushed into the hair whereupon the members A and B are brought together as shown in solid lines in Figure 2, the forward bent portion 23 of the member B snapping behind the curved nose 22 of the strip 20 of member A. The hair is thus seized between the two members as shown in Figure 5 of the drawing and is incidentally given a slight vertical wave as indicated.

The member A is then expanded by forcing the rear end 27 of the strip 20 forwardly beneath the sleeve 18 whereupon the strip 20 is bowed outwardly to the position shown in dotted lines in Figure 2, the bight 29 resting snugly against the sleeve 18 and serving to retain the elements in this position. The hair is then closely confined between the uppermost element 30 and the strip 20 and beneath the wire frame 16 as clearly shown in Figure 6 of the drawing, the comb-like teeth 36 extending through the hair and entering the slot 25 in the member 20. This position is also shown in longitudinal section in Figure 7 of the drawing.

Thus far, there has been applied to the hair a vertical wave which, if the device is allowed to remain in position for a sufficient length of time, will become set and will remain for a considerable period of time after the appliance has been removed. However, by sliding the element 30 toward the forward end of the device, the central portion of the quantity of hair confined between the members A and B will be curved forwardly in a plane transverse to that of the initial curvature applied as in Figure 6. This additional curvature or undulation is effected by the comb

teeth 36 moving in the slot 25 as clearly shown in Figure 8 of the drawing.

After being applied for sufficient time for the wave to become set, the device is removed by sliding the element 30 rearwardly, and releasing the strip 20 by pressing upon the bowed portion 27 thereof until the bight 29 moves past the sleeve 28 and the strip resumes its position shown in solid lines in Figure 2. Finally the members A and B are separated by moving the forward end 23 of the wire 16 past the nose 22 of the strip 20 by compressing the convex parts of B at 17 and lifting member B up.

It will be understood that several of these devices may be applied to the hair at one time since they are of very light construction, and the hair may be treated or manipulated in any desired manner to aid in preserving the wave.

It will be further understood that various changes and modifications may be made in the illustrated form of the device, without departing from the scope of the invention as defined by the following claims.

As employed in the claims, the terms "vertical" and "horizontal" are meant to indicate the direction of curvature of the wave with respect to the scalp. When the wave lies in a plane substantially vertical with respect to the scalp at the point where the wave occurs, the term "vertical" will be applied to the wave or undulation, and when the wave is substantially parallel with the scalp at any point, the term "horizontal" will be employed.

Having thus described the invention, what is claimed as new and desired to be secured by Letters Patent is:

1. A hair waving appliance of the class described, comprising, in combination, elongated members for confining a block of hair, one of said members provided with an element shiftable toward the other of said members to apply a vertical wave to the hair, another element adapted to cooperate with said members to impart a substantially horizontal wave to the hair, and means affording a readily detachable connection between said last named element and the vertical waving portion of the appliance.

2. A hair waving appliance of the class described comprising, in combination, elongated members for confining a block of hair, one of said members provided with an element shiftable toward the other of said members to apply a vertical wave to the hair, an element movably carried by one of said members and adapted to cooperate with said members to impart a substantially horizontal wave to the hair, and means affording a readily detachable connection between said last named element and the vertical waving portion of the appliance.

3. A hair waving appliance comprising elongated inner and outer hair confining members between which hair to be waved may be freely inserted, one of said members including an elongated flexible element having one end fixed and the other end free, said element being adapted to be laterally distorted toward the other members when longitudinal pressure is applied to the free end to cause hair positioned between said members to be closely engaged between said element and the other of said members, said last named other member provided with a movable section having portions for engaging the hair and imparting a horizontal wave thereto when said section is moved.

4. A hair waving appliance of the class de-

scribed comprising, in combination, a pair of elongated hair confining and waving members pivotally connected together at corresponding ends and adapted to be closed upon a quantity 5 of hair to be waved; one of said members comprising a curved base element having a flexible strip attached thereto, extending generally parallel therewith, and capable of being bowed toward the other of said members to apply a vertical wave 10 to the confined hair; said other member comprising a frame having side rails spaced apart a distance greater than the width of said strip; means for latching the free ends of said members together when closed; means for retaining 15 said strip in bowed position and means for releasing it therefrom; and a toothed element slidably mounted upon said side rails for contacting the confined hair and applying a horizontal wave thereto when moved along said rails.

20 5. A hair waving appliance of the class described comprising, in combination, a pair of elongated hair confining and waving members pivotally connected together at corresponding ends and adapted to be closed upon a quantity of 25 hair to be waved; one of said members comprising a curved base element having a flexible strip attached thereto, extending generally parallel therewith, and capable of being bowed toward the other of said members to apply a vertical 30 wave to the confined hair; said other member comprising a substantially rectangular wire frame having side rails spaced apart a distance greater than the width of said strip; means for latching the free ends of said members together when 35 closed; means for retaining said strip in bowed position and means for releasing it therefrom; and a toothed element slidably and detachably mounted upon said side rails for contacting the confined hair and applying a horizontal wave 40 thereto when moved along said rails.

6. A hair waving appliance of the class described comprising, in combination, a pair of pivotally connected elongated hair confining and waving members; one of said members having a bowed flexible element secured thereto, and bent to provide a rounded surface, the other of said

elements having a loop portion adapted to snap past said rounded surface in order to retain the pivoted members in closed operative positions.

7. A hair waving appliance of the class described comprising, in combination, a pair of 5 pivotally connected elongated hair confining and waving members, one of said members comprising a base element and a flexible strip secured to said base element and bent sharply adjacent its point of attachment therewith and adapted to 10 be projected toward the other of said members in order to impart a wave to the hair, said other member including a wire loop which, when said members are closed, is adapted to be snapped past said bent portion of said strip in order to 15 latch the members in said closed position.

8. A hair waving appliance of the class described comprising, in combination, elongated members for confining a block of hair and applying a vertical wave thereto, a supplemental member 20 adapted to cooperate with said first named members to impart a substantially horizontal wave to said block of hair, and means affording a readily detachable connection between said supplemental member and the vertical waving portion 25 of the appliance.

9. In combination, with a device for applying a vertical wave to a block of hair, an attachment for cooperating with said device to apply a horizontal wave to said block of hair, said attachment 30 comprising a member having a plate-like body portion provided with a series of teeth for engagement with said block of hair, and resilient clamping means on said member whereby it may be readily and detachably snapped into operative 35 engagement with said device.

10. As an article of manufacture, an attachment for hair waving appliances comprising a member having a plate-like body portion provided with a plurality of teeth for engaging a block of 40 hair, a plurality of legs extending from said plate-like body portion, and resilient clamping means on said legs for readily and detachably connecting said member with said appliance.
